EJECTOR NOZZLE

Robert A. Whitlock, Jr., Rockford, Ill., assignor to Automatic Pump & Softener Corporation, Rockford, Ill., a corporation of Illinois

Application December 14, 1951, Serial No. 261,619

3 Claims. (Cl. 103—278)

This invention relates to an ejector nozzle.

It is an object of this invention to provide an adjustable ejector nozzle which is operative in all of the positions to which it is adjusted to pass a jet of fluid.

Another object of this invention is to provide an ejector nozzle having a needle valve therein which is adjustable for selectively varying the flow of fluid through the nozzle and which in all the positions to which it may be adjusted is operative to pass a jet of fluid through the nozzle.

It is also an object of this invention to provide an ejector nozzle having an adjustable needle valve controlling the flow of fluid out the discharge port of the nozzle, wherein the needle valve is operative in one extreme limit of its adjustment to block the nozzle discharge passage and establish a minimum discharge flow through the needle valve itself and is operative in its opposite extreme limit of movement to be retracted from the nozzle discharge passage to permit a maximum flow therethrough.

A further object of this invention is to provide an ejector nozzle with an adjustable needle valve therein for controlling the flow through the nozzle having a novel arrangement for maintaining the needle valve properly located in the position to which it has been adjusted.

A still further object of this invention is to provide an ejector nozzle with an adjustable needle valve therein for controlling the flow through the nozzle having a novel arrangement for resisting any undesired displacement of the needle valve in response to the flow of fluid through the nozzle.

Yet another object of this invention is the provision of an ejector nozzle with an adjustable needle valve therein for controlling the flow through the nozzle having novel means for preventing leakage of fluid between the needle valve and the nozzle.

Other and further objects and advantages of the present invention will be apparent from the following description of a preferred embodiment thereof, which is shown in the drawing to illustrate the principles of the invention.

In the drawing:

Figure 1 is a fragmentary cross-section of a lift-turn valve used in a water treatment system having the ejector nozzle of the present invention incorporated therein;

Figure 2 is a longitudinal cross-section of the ejector nozzle of the present invention, with the adjustable needle valve therein in a retracted position;

Figure 3 is a fragmentary longitudinal cross-section of the Fig. 2 device, with the needle valve positioned to block the discharge passage of the nozzle;

Figure 4 is a fragmentary longitudinal cross-section of the threaded, mounted end of the needle valve incorporated in the ejector nozzle of the present invention; and

Figure 5 is a fragmentary cross-section taken transverse to the Fig. 4 view, and showing the threaded, mounted end of the adjustable needle valve for the ejector nozzle.

Referring to Fig. 1, the ejector of the present invention is shown in conjunction with a lift-turn valve commonly used in water treatment apparatus, such as water softeners. The lift-turn valve includes a back plate 11 which is separated from the upper valve chamber 12 by an angularly adjustable rotor 13. In one position of the valve rotor 13, the port 14 therein registers with an inlet passage 15 in the back plate which communicates with a chamber 16 in which is located the ejector nozzle 17 of the present invention. A brine inlet 18 in the back plate 11 communicates with a passage 19 which is located between the discharge end of the ejector nozzle 17 and the venturi shaped throat 20 of the ejector. In operation, water passes from the upper valve chamber 12 down into passage 16 and thence through the ejector nozzle, the stream of water discharged from the ejector nozzle drawing brine through inlet 18 into the throat 20 of the ejector, after which the brine solution passes to the water softener tank for regenerating the bed of water softening material therein.

From Fig. 2 it will be seen that the ejector nozzle 17 is formed with a generally cylindrical outer nozzle body formed intermediate its extent with a plurality of circumferentially spaced inlet passages 21, which incline inwardly toward the discharge passage 22 in the nozzle. Toward its discharge end the ejector nozzle is externally threaded at 23 to be adjustably received in the end wall 24 of the passage 19 in the back plate of the valve. A longitudinal, substantially cylindrical passage 25 is formed in the outer nozzle body to effect communication between the inlet passages 21 and the discharge passage 22. At 26 the nozzle passage 25 tapers inwardly toward its juncture with the smaller discharge passage 22.

For a substantial portion of its length away from the discharge passage 22 the nozzle passage 25 is internally threaded at 27 for receiving the enlarged externally threaded rear end 28 of the needle valve. At its rear face the needle valve is provided with a slot 30 for the reception of a screw driver for effecting adjustment of the needle valve within the nozzle. An elongated stem portion 29 of the needle valve, of smaller cross-sectional size than the nozzle passage 25, extends forward within the nozzle passage and terminates in a tapered forward end 32 which is adapted to extend into the nozzle discharge passage 22 and completely block the latter. As best seen in Fig. 3, in the extreme forward limit of adjustment of the needle valve, a portion of its tapered forward end 32 is seated against the juncture of the discharge passage 22 and the inwardly inclined portion 26 of the nozzle passage 25.

At its forward end the needle valve stem 29 is formed with a longitudinal passage 33 which terminates in a port at the front face of the stem 29 which is centrally aligned with the nozzle discharge passage 22. Adjacent its other end the needle valve passage 33 communicates with a transverse passage 34, which inclines inwardly and forwardly from the periphery of the valve stem. When the forward end 32 of the valve stem is seated within the nozzle discharge passage 22 to block the latter (Fig. 3), the valve stem passages 34 and 33 pass water from the nozzle passage 25 out the discharge end of the nozzle. Thus, the needle valve provides a minimum flow through the ejector nozzle when the requirements of the system dictate such a minimum flow. When the needle valve is full retracted the maximum flow occurs through the ejector nozzle, this maximum flow being determined by the size of the nozzle discharge passage 22. Between these two extremes, the needle valve is operative to set the flow through the ejector nozzle at any desired value to adapt the nozzle to the needs of the particular system. Obviously, this adjustability of the ejector nozzle renders

it readily adaptable to systems of widely different sizes and capacities.

In the use of this device it was found that the water passing through the needle valve passages 34, 33 exerted a twisting force on the needle valve tending to twist the same, so as to screw it forward or backward along the nozzle passage 25 away from the position to which it had been adjusted. To avoid any such undesired displacement of the needle valve, the latter is formed at its threaded rear end with a transverse, diametrically extending drilled hole 35 for receiving a cylindrical resilient insert 36 of rubber or other suitable material capable of deforming under pressure and of returning to its original shape. The insert 36 initially is of substantially the same cross-section as the hole 35, but capable of being manually inserted therein. Initially the insert 36 is about $\frac{1}{32}$ inch longer than the major diameter of the threaded portion 28 of the needle valve so as to project beyond the threads thereon at diametrically opposed areas thereof at the opposite ends of the hole 35. When the needle valve is first screwed into the threaded portion 27 of the axial nozzle passage 25 the insert 36 is compressed at both ends until it snugly fills the drilled hole 35, after which the insert exerts a compressive force against the female threads at 27. It is to be noted that the compressive force of the insert 36 against the female threads 27 is at diametrically opposite locations on the needle valve so that the needle valve is maintained properly centered within the outer nozzle. This is quite important in order to insure that the discharge through the needle valve passage 33 is aligned with the discharge passage 22 in the nozzle. To add to the locking action of the insert 36, after awhile there is a certain amount of vulcanization which seals the insert 36 to the adjacent threaded portion 27, in the event that the insert contains an appreciable amount of natural rubber or certain synthetic rubbers, such as neoprenes, known to have that reaction with certain metals, and the threaded portion 27 is of brass or other metal, such as silver, known to have the described reaction with the natural or synthetic rubbers.

For preventing leakage between the threaded rear end 28 of the needle valve and the threaded portion 27 of the nozzle, there is provided an O-ring 37 of resilient material, such as rubber, seated against a transverse, flat, annular face 38 formed on the nozzle immediately behind the threaded portion 27 thereof. An enlarged head 39 is formed on the nozzle and provides an internal threaded axial passage 40 immediately behind the face 38. An externally threaded hollow cap member 41, which has its outer end closed by an externally knurled head 42, is threaded received in the threaded passage 40. At its inner end the cap member terminates in an annular face 43, which tapers forwardly and inwardly for engagement with the O-ring 37 to compress the latter. The knurled head 42 permits the cap 41 to be manually screwed in to cause its tapered inner end face 43 to distort the O-ring for effecting a positive seal at the rear end of the threaded portion 27 of the nozzle. When it is desired to change the position of the needle valve axially within the nozzle, the cap 41 may be screwed out manually and the desired adjustment of the needle valve accomplished by a screw driver engaging in the slotted end 30 of the needle valve.

While in the foregoing description there is disclosed a specific preferred embodiment of the present invention, it is to be understood that various changes and modifications which depart from the described form of the invention may be adopted without departing from the spirit and scope of my invention.

I claim:

1. A screw-in nozzle unit comprising an outer nozzle body formed with a discharge passage terminating in a discharge opening at the forward end of the body, said body adjacent its forward end being threaded externally and forward of said externally threaded portion having its periphery terminate short of the outer

periphery of said externally threaded portion to permit screw-in insertion of the forward end of the outer nozzle body in a supporting structure, said outer nozzle body immediately behind its externally threaded portion having a cylindrical periphery and formed therewith a plurality of inlet passages for admitting fluid to said discharge passage from outside the nozzle body, said body having an enlarged annular, internally threaded portion formed integrally on the rear end of said cylindrical portion and defining therewith an annular external shoulder for limiting insertion of the nozzle unit in the supporting structure and an annular inner shoulder, said cylindrical portion of said body being internally threaded, a needle valve having an externally threaded portion threadedly received in said cylindrical portion and having a stem projecting forwardly therefrom to control the flow of fluid through said discharge opening, a resilient O-ring seated against said inner shoulder, and an externally threaded cap threadedly received in said enlarged portion on the outer nozzle body, said cap member being formed at its inner end with an annular face for engaging said O-ring to compress the latter against said inner shoulder and thereby seal the rear end of said nozzle body.

2. A screw-in nozzle unit comprising an outer nozzle body formed with a discharge passage terminating in a discharge opening at the forward end of the body, said body adjacent its forward end being threaded externally and forward of said externally threaded portion having its periphery terminate short of the outer periphery of said externally threaded portion to permit screw-in insertion of the forward end of the outer nozzle body in a supporting structure, said outer nozzle body immediately behind its externally threaded portion having a cylindrical periphery and formed therewith a plurality of inlet passages for admitting fluid to said discharge passage from outside the nozzle body, said body having an enlarged, annular, internally threaded portion formed integrally on the rear end of said cylindrical portion and defining therewith an annular external shoulder for limiting insertion of the nozzle unit in the supporting structure and an annular inner shoulder, said cylindrical portion of said body being internally threaded, a needle valve having an externally threaded portion threadedly received in said cylindrical portion and having a stem projecting forwardly therefrom to control the flow of fluid through said discharge opening, a resilient O-ring seated against the inner shoulder 15, and an externally threaded cap threadedly received in said enlarged portion on the outer nozzle body, said cap member being formed at its inner end with a forwardly and inwardly tapered annular face for engaging said O-ring to compress the latter against said inner shoulder and the inner walls of said enlarged portion on said nozzle body and thereby seal the rear end of the nozzle body.

3. A screw-in nozzle unit comprising an outer nozzle body formed with a discharge passage terminating in a discharge opening at the forward end of the body, said body adjacent its forward end being threaded externally and forward of said externally threaded portion having its periphery terminate short of the outer periphery of said externally threaded portion to permit screw-in insertion of the forward end of the outer nozzle body in a supporting structure, said outer nozzle body immediately behind its externally threaded portion having a cylindrical periphery and formed therewith a plurality of inlet passages for admitting fluid to said discharge passage from outside the nozzle body, said body having an enlarged, annular, internally threaded portion formed integrally on the rear end of said cylindrical portion and defining therewith an annular external shoulder for limiting insertion of the nozzle unit in the supporting structure and an annular inner shoulder, said cylindrical portion of said body be-

ing internally threaded, a needle valve having an externally threaded portion threadedly received in said cylindrical portion and having a stem projecting forwardly therefrom to control the flow of fluid through said discharge opening, a resilient O-ring seated against said inner shoulder, and an externally threaded cap threadedly received in said enlarged portion on the outer nozzle body, said cap member being hollow and having an inner diameter greater than the outer diameter of the threaded portion on said needle valve, said cap member being formed on its inner end with a forwardly and inwardly tapering annular face for engaging said O-ring to compress the latter against said inner shoulder and the inner walls of said enlarged portion on said nozzle body and thereby seal the rear end of the nozzle 15 body.
